VALVE FOR OIL WELL SWABS

Robert B. Fraser, Ventura, Calif.

Application December 19, 1940, Serial No. 370,778

4 Claims. (Cl. 251—118)

My invention relates to a valve for a well swab, particularly adapted for oil wells.

One of the principal objects of this invention is to provide a well swab valve of this class for cleaning oil well casings or tubings without employing exterior rubber members or other readily deleterious members.

Another important object of this invention is to provide a well swab valve of this class having operating members which will not readily deteriorate or get out of order, and one which may be readily disassembled and in which the various elements are readily accessible.

An important object also of this invention is to provide a well swab valve of this class which may be easily operated, which may be lowered into or raised from the well with considerable speed, and which will operate automatically to avoid overloads.

A further object of this invention is to provide a well swab valve of this class which may not be readily damaged by sudden operation or movement in either direction.

With these and other objects in view, as will appear hereinafter, I have devised a well swab valve having certain novel features of construction, combination, and arrangement of parts and portions, as will be hereinafter described in detail and particularly set forth in the appended claims, reference being had to the accompanying drawing, and to the characters of reference thereon, which form a part of this application, in which:

Fig. 1 is a fragmentary elevation of an oil well showing my well swab, in one form, in position therein;

Fig. 2 is a fragmentary longitudinal sectional view thereof; and,

Figs. 3 and 4 are transverse sectional views thereof, taken, respectively, through 3—3, and 4—4 of Fig. 2.

The oil well casing, designated 1, and in which my device is used, is substantially of uniform inside diameter. My well swab is constructed to fit substantially the inside of the casing for cleaning or swabbing the same.

The housing or casing of my swab, as shown in the drawing, may consist of a rope socket member 11, an upper tubular casing 12, a lower tubular casing 13, an upper tube or pipe length or section 14, connecting the casing 12 to the rope socket member, a lower tube or pipe section 15, extending below the casing 13, and a lower guide or end piece 16 secured to the lower end of the pipe

section 15. The pipe sections 14 and 15 are added principally for the purpose of adding weight.

All of these members may be only one-eighth of an inch less in diameter than the inside diameter of the well casing 1. On the upper tubular casing 12 is provided a pair of spaced sealing rings 17 and 18 which frictionally engage the inner walls of the well casing. These sealing rings are self expanding, and those shown are only by way of example.

The string just mentioned is suspended in and is raised or lowered within the well casing by a suitable rope 21 which enters the axial portion of the rope socket member and is secured at its end thereto in any suitable manner, such as shown in the drawing.

Within the lower end of the casing 12 is provided a cylinder member 31 which may be pressed therein and engages at its lower end an annular shoulder 13^a near the upper end of the casing 13. Within and at the axial portion of the cylinder member 31 is reciprocally mounted a piston 32 which is so movable within the cylinder that its ends are extensible beyond the ends thereof, as will be described hereafter. The opposite ends of the inner wall of the cylinder member may be fluted, as indicated by 31^a and 31^b. If desired, the upper end of the piston may also be longitudinally fluted, as indicated by 32^a. This piston is provided intermediate its ends with spaced sealing rings 33 so that the portion between the rings may be sealed with respect to the opposite ends of the cylinder member.

Within the casing 13 is a compression spring 41 which is seated at its lower end on a shoulder 13^b of the casing. At the upper end of the spring is a washer 42 which is adapted to engage the lower end of the cylinder member to limit the upward movement of the spring to a position below the lower end of the cylinder member 31. This washer 42 is provided with ports near the periphery, that is, radially outwardly from the central portion, which central portion is engageable by the piston. Thus, the spring 41 is permitted to act directly upon the piston and force the same flush with the lower end of the cylinder member.

Within the casing 12 is a stop or anvil 51 which is circular in form and rests upon an annular shoulder 12^a. This anvil is forced against the shoulder from the upper side by a spring 52 which is held in position by a transverse pin 53.

The guide or lower end piece 16, which is se-

cured to the lower end of the casing 13, or, as shown, to the lower end of the pipe section 15, has an axial bore extending to its lower end. When the string is lowered into the well, a screw plug 61 is screwed into the lower end of the guide or end piece, as indicated by dotted lines in Fig. 2. As soon as liquid in the well is encountered, and the depth thereof is noted, the string is withdrawn and the screw plug 61 removed.

The swabbing operation is then begun. The string is again lowered into the well, to the desired depth below the surface of the liquid. Such lowering causes the piston 32 to be raised. But the anvil 51 stops such upward movement, the spring 52 taking the recoil. Continued lowering of the string will allow the liquid, mud, and the like, to by-pass the piston, through the longitudinal flutes 31^a, and to flow out at the top through openings 11^a in the rope socket, the latter openings radiating from the bore of the rope socket member, and are directed upwardly at an angle. As the string is raised, the material to be cleaned from the well enters the interior of the casing 12 through the transverse openings 11^a. Raising of the well swab causes the piston to return to its normal lower sealing position, shown by solid lines in Fig. 2. When the load within the swab becomes too great, the piston 32 is forced down beyond said normal position and is permitted by the spring 41 to recede, until the flutes 31^b at the lower end of the cylinder member, or the flutes 32^a at the upper end of the piston, or both, allow the excess liquid, mud, or the like, to by-pass the piston, and to pass through the lower end of the casing 13 and the end piece 16 back into the well below the swab. Such action prevents overloading of the rope, and serves as a safety means.

Though I have shown and described a particular construction, combination, and arrangement of parts and portions of my well swab valve, I do not wish to be limited to the same, but desire to include in the scope of my invention the construction, combination, and arrangement substantially as set forth in the appended claims.

I claim:

1. In a well swab, a cylinder open at the upper and lower portions, a tubular casing for supporting the cylinder, a piston reciprocally mounted within the cylinder, the cylinder and piston being so constructed as to provide by-pass means between the cylinder and piston when the latter is at either end of its stroke, a single spring for urging the piston upwardly to an intermediate position in which the cylinder is sealed by the piston, and a resilient bumper for limiting the upward, opening movement of the piston.

2. In a means of the class described, a tubular casing, a tubular cylinder within the casing, a piston reciprocally mounted within the cylinder,

the lower portion of the inner wall of the cylinder having longitudinal flutes, a stop washer, and a spring positioned in the casing below the cylinder for urging the washer against the cylinder at the lower ends of the fluted portion thereof, said washer having openings communicating with the lower ends of the flutes, the piston being adapted normally to rest upon the central portion of the washer to close the bore of the cylinder.

3. In a means of the class described, a tubular casing, a tubular cylinder within the casing, a piston reciprocally mounted within the cylinder for closing the bore thereof, the upper portion of the inner wall of the cylinder having longitudinal flutes, means for limiting the lower position of the piston, a spring positioned within the casing above the cylinder, means for limiting the movement of the upper end of the spring within the casing, a perforated washer, there being provided an annular shoulder in the casing above the cylinder, the spring being adapted to urge the washer against the shoulder, the upper end of the piston being normally spaced below the washer, the piston being capable of being forced upwardly with its upper end above the cylinder and adapted, when so moved, to engage the central portion of the washer and unseat said washer from said shoulder against the force of said spring and open the bore of the cylinder.

4. In a means of the class described, a tubular casing, a tubular cylinder within and at the intermediate portions of the casing, a piston reciprocally mounted within the cylinder, the lower and upper portions of the inner wall of the cylinder having longitudinal flutes, a stop washer, a spring positioned in the casing below the cylinder for urging the washer against the cylinder at the lower ends of the fluted portion thereof, said washer having openings communicating with the lower ends of the flutes, the piston being adapted to rest upon the central portion of the washer to close the bore of the cylinder, a second spring positioned within the casing above the cylinder, means for limiting the movement of the upper end of the latter spring within the casing, a perforated washer, there being provided an annular shoulder in the casing above the cylinder, the latter spring being adapted to urge the latter washer against the shoulder, the upper end of the piston being normally spaced below the latter washer, the piston being capable of being forced upwardly with its upper end above the cylinder and adapted, when so moved, to open said bore and to engage the central portion of the latter washer and unseat the same from said shoulder against the force of said spring.
